UNITED STATES PATENT OFFICE.

ALBIN E. S. FAGERHOLM, OF BROOKLYN, NEW YORK, ASSIGNOR TO NELS A. NELSON,
OF BROOKLYN, NEW YORK.

EXPLOSIVE-ENGINE.

1,089,194.

Specification of Letters Patent.

Patented Mar. 3, 1914.

Application filed December 16, 1911. Serial No. 666,096.

To all whom it may concern:

Be it known that I, ALBIN E. S. FAGERHOLM, a subject of the King of Sweden, residing at Brooklyn, in the county of Kings and State of New York, have invented new and useful Improvements in Explosive-Engines, of which the following is a specification.

This invention relates to gas engines and more especially to cylinders for same and where the cylinder is provided with a false head retained in place by spring pressure but which is adapted to yield when the explosion of the gas takes place as will be more fully described in the following specification, set forth in the claim, and illustrated in the drawings, wherein,

Figure 1 is a sectional view of the same, showing the improved head applied thereto. Fig. 2 is a similar view at right angle to Fig. 1. Fig. 3 is a plan view of the yoke for carrying the spring.

The cylinder 5 is of usual construction and is provided with the water jacket to cool same. The spark plug 6 is located on the line of the highest movement of the piston 7, which is provided with the usual pitman 8 connecting it with the crank shaft 9.

The piston is dished on its upper side in order to provide a chamber between itself and the false head 10 which is likewise dished. The piston and the head are provided with upwardly projecting studs 12 which pass through a chamber 13 and the upper end 14 of the cylinder. They are then connected with a yoke 15 which conforms with the top of the cylinder and has overhanging arms 16 perforated to receive the ends of springs 17. The other ends of these springs 17 are connected with the frame 18 of the engine by means of bolts 19 and nuts 20.

At one side of the cylinder is an exhaust port 21 with the usual valve 22, which permits the burnt gases to escape into the muffler 23. The chamber 13 is also connected by means of an outlet 24 with the muffler in order to allow the head 10 to move upward and have its movement limited by the spring 17 only. At the other side of the cylinder is a manually operated vent cock 25 to relieve the cylinder of any undue accumulation of exploded gases.

In the operation of the engine the explosive mixture is drawn by piston action 55 through a lateral valve controlled inlet port (not shown) and when the gas or vapor is exploded, its force is exerted as usual, upon the piston and upon the false head 10 which yields in accordance with the strength of the 60 spring or the load put upon the engine. The use of this false head relieves the engine of considerable strain and unnecessary noises, and it is obvious that if desired, the springs 65 may be removed and the yoke 15 bolted down so as to form a solid head to the cylinder. The springs may be adjusted by means of the bolts 19 and nuts 20 or lighter springs may be substituted as desired.

As illustrated in Fig. 2 of the drawing the piston 7 is arranged so that at one end of its stroke it covers the inner end of the passage 21. Therefore the valve 22 located in the passage 21 is relieved of excessive pressure when the charge between the piston 7 and 75 the head 10 is receiving its final compression and also the said valve 22 is relieved from sudden shock during the initial expansion of the charge immediately after it has been fired.

What I claim as new and desire to secure by Letters Patent is—

An engine comprising a cylinder provided at its side with an exhaust passage, a piston slidably mounted in the cylinder, and arranged to move over the exhaust passage, a head movably mounted in the cylinder between the exhaust passage and the end of the cylinder, studs attached to the head and slidably passing through the end of the cylinder, a yoke attached to the studs, and springs connected with the yoke and the cylinder and normally holding the yoke against the end of the cylinder said studs and yoke arranged to co-operate with the cylinder to limit the movement of the head in the cylinder to a path between the exhaust passage and the end of the cylinder.

In testimony whereof I affix my signature in presence of two witnesses.

ALBIN E. S. FAGERHOLM.
